CUTTING TORCH

Filed Dec. 15, 1928

UNITED STATES PATENT OFFICE

GEORGE C. QUELCH, OF OAKMONT, PENNSYLVANIA, ASSIGNOR, BY MESNE ASSIGNMENTS, TO UNION CARBIDE AND CARBON RESEARCH LABORATORIES, INC., OF NEW YORK, N.Y., A CORPORATION OF NEW YORK

CUTTING TORCH

Application filed December 15, 1928. Serial No. 326,313.

My invention refers to an improvement in the class of torches for the cutting of ferrous metals.

In such torches, which are now in large and common use, a pre-heating flame of high temperature is first directed against the metal to be cut, and, when the combustible temperature of the metal is reached, a jet of pure oxygen under pressure is directed against the heated portion, (with a corresponding cessation of the pre-heating flame).

Combustion of the metal, under the oxygen jet, then occurs, reducing the metal to magnetic oxide of iron, the pressure jet of oxygen forcing the oxide through and away from the narrow curl made in the metal as the cutting action proceeds along a given line.

In torches of this general class, the device is usually provided with three supply pipes or conduits, leading to the terminal head embodying the tip, providing for the supply of high pressure oxygen for cutting, pre-heating oxygen, and a combustible gas for burning therewith for pre-heating.

In general practice, there are two main classes or types of tips utilized; first, where the combustible mixture of oxygen and fuel gas, for pre-heating, is formed or combined within the torch proper or within its head; second, where the combustible mixture is formed between balanced gases, or by proper relation of the conducting orifices, or by injector action within the torch tip itself, mounted in the surrounding head.

There are also variations in the terminal construction of the tip, which may be either plane across the delivery end with all of the jet openings emerging on the same plane, or with the tip of the jet recessed, providing a forwardly extending tubular shell for protection of the pre-heating flame.

The plain end tips are ordinarily used for fuel gases having a kindling or igniting point below 600° C., such as hydrogen, igniting with an igniting point of 580° C., or acetylene at 480° C.

The recessed tips are ordinarily used for fuel gases having a kindling or igniting point above 600° C., as in the case of hydrocarbon gases, which liquefy within a container at or

below the pressures usually considered standard for low or high pressure containers.

In the use of such gases for metal cutting with torches of the class involved, it has been necessary, and the practice is common in the industry, to use a tip designated as a recessed tip.

The object of my present invention is to provide a cutting torch tip for the purpose of securing a more stable pre-heating flame with a gaseous mixture of high kindling or igniting point, as above 600° C.

These objects are secured in my present construction by means of adjustable mechanism adapted to very accurately regulate the supply of the pre-heating oxygen and fuel gas, in exact desired proportions, by means of a positively adjustable regulating ported shell in communication with the pre-heating oxygen supply, operable in relation to the gas supply ports, with a view to further thorough commingling intermixture.

Also by means of the annular mixing chambers, and terminal emission slots, to further thoroughly mix the combustion fuel, with preliminary pre-heating, before final emission.

These and other objects in connection with the complete tool, as assembled, are accomplished by the construction herein shown and described.

In the accompanying drawings showing one preferred embodiment of the invention:

Fig. 1 is a view in elevation of a complete head of a cutting torch;

Fig. 2 is an enlarged vertical section thereof, partly in elevation;

Fig. 3 is a detached vertical sectional view of the middle high pressure oxygen supply burner tip;

Fig. 4 is a detached vertical sectional view of the mixing shell;

Fig. 5 is a detached view in elevation of the perforated adjusting plug for said shell;

Fig. 6 is a transverse section on the line VI—VI of Fig. 2, through the high pressure oxygen supply conduit;

Fig. 7 is a similar view on the line VII—VII of Fig. 2, through the low pressure oxygen supply conduit;

Fig. 8 is a similar view on the line 100

VIII—VIII of Fig. 2, through the gas supply conduit.

Referring to the drawings, A is the head of a standard torch having the usual high pressure oxygen supply pipe 2, a low pressure oxygen supply pipe 3, and a gas supply pipe 4 communicating with the several corresponding supply passages 5, 6 and 7 through the head A.

- 10 As is generally understood and practiced in the art, the pre-heating mixture is formed by mixing the low pressure oxygen from port 6 with the pre-heating gas, as acetylene, hydrocarbon, etc., delivered through port or ports 7.

Jet member *a* is generally similar to such members of standard torches in that it is provided with the central high pressure oxygen passage 8 communicating through a terminal plug 35, with a chamber 9 in head A to which high pressure oxygen is delivered through port 5.

- 20 Jet member *a* extends downwardly by its lower delivery portion within the surrounding outer casing or shell 10, both members having interfitting tapered connection at the delivery end of the torch as shown, the terminal 11 of the jet member fitting within the outer tapered terminal 12 of the shell and preferably terminating backwardly therefrom, leaving the receded emission space 13.

- 25 Shell 10 is enlarged at its inner portion 10a, providing a cylindrical head in substantially tight engagement within the surrounding head A by a tight tapered seat engagement thereagainst, as by the beveled shoulders 14.

- 30 A narrow annular space 10b intervenes between the head A and portion 10a for gas circulation, as hereinafter described.

- 35 The shell is tightly secured in place by nut 15 having surrounding engagement with the shell and against a tapered sealing washer 16 and screw connection 17 with the lower portion of head A.

- 40 Enlarged head portion 10a of the shell is annularly recessed as at 18, providing an inner wall having a plurality of transverse ports 19 of any suitable number, as eight, by which fuel gas communicates through annular space 10b from the registering ports 7 to the interior annular cavity 20 between the inner wall of the shell and the main upper reduced stem 21 of jet member *a*.

- 45 Said member as shown is shouldered as at 22, leaving an increased width of the annular space 20 with relation to the subsequent lower annular space 23 between the jet member and the shell downwardly below the larger annular space 20.

- 50 Immediately beyond the practically tight connection between the tapered members of the inner and outer parts 11—12, jet member *a* is increased in diameter as at 24, fitting tightly within the cylindrical portion of shell 10, and the jet member is provided at such

location with the tapered delivery slots 25.

Such slots extend from a slight distance inwardly beyond the closing rim 24 through the outer portion of the jet member clear to its end, as clearly shown in Fig. 3. They are milled or otherwise formed longitudinally of the jet member, and are of the greatest depth between their inlet and outlet terminals, so that the fuel mixture will be retarded in passing therethrough, with ample opportunity for pre-heating within the terminal shell 12, at the zone of combustion.

55 Ports 25 may be of any suitable number, as six, arranged equidistantly around the delivery end of the jet member, and serve to deliver the thoroughly mixed fuel gas and oxygen outwardly through recessed cavity 13 of the tapered shell terminal 12.

60 Immediately beyond the shouldered engagement 14 the head A is provided with an annular chamber 26 to which pre-heating oxygen is delivered by port 6. A mixing shell 27 is threaded by its upper end at 28 into the upper inner portion of head A, and is also threaded into the inner upper portion of head 10a of shell 10, as at 29. The lower portion of shell 27 is reduced in external diameter, providing the extended tubular terminal 30, the outer and inner portions of which are smooth and unthreaded, as shown.

65 When the shell is inserted in position as in Fig. 2, the outer circumference of terminal 30 is spaced inwardly from the interior wall of head 10a, leaving a comparatively shallow annular space 31. The inner surface of terminal 30 is similarly spaced outwardly beyond the reduced neck 21 of tip *a*, leaving a similar shallow intervening annular cavity 32.

70 Terminal 30 is provided with a plurality of transverse ports 33 of any suitable number, as six, equally spaced, for pre-heating oxygen circulation, and the shell is provided with two or more oppositely spaced angular perforating ports 34, communicating between the annular chamber 26 and such annular space 32.

75 Adjusting plug 35 is screwed into the upper portion of shell 27, the plug having a central circulation opening registering with the high pressure oxygen perforation 8 of the main inner stem, and is also provided with a transverse slot 36 for adjustment by a screw driver.

80 The plug acts as a limiting abutment which, by rotation, may be very accurately set to the desired position, to limit the relative position of the shell 27 on the upper threaded portion of stem 21 of member *a*, so that when said member is in operative position as in Fig. 2, the lower edge of terminal 30 will be exactly adjusted with relation to the gas circulation ports 19, in the manner of a valve.

85 Thus by lengthening or shortening the combined central stem and its shell, the lower edge of terminal 30 will act as a valve for

admitting the proper desired amount of fuel gas to the annular spaces 20 and 31.

By screwing stem 21 upwardly into tight jamming position within shell 27 and against abutment 35, as adjusted, the parts will be fixedly held in proper position, and may be very easily and accurately regulated for a greater or less supply of gas, by merely loosening the plug 35 and making a further adjustment of the shell on the jet member, such adjustment being made by merely unscrewing the surrounding shell 10 and the jet member from the head, with ultimate replacement therein.

15 As thus constructed and assembled, the parts being in proper operative relation, the operation is as follows.

Fuel gas being supplied through conduit 4 and ports 7 to annular chamber 18 will pass 20 inwardly through ports 19, as controlled by the partly covering edge of terminal 30. Pre-heating oxygen delivered through port 6 to annular chamber 26 will pass inwardly through shell 27 by ports 34 into inner annular space 32 and to the main mixing space 20.

A portion of oxygen however, will pass outwardly through ports 33 and become mixed with gas in annular space 31. Ultimately all of the pre-heating oxygen and fuel gas pass 30 to the enlarged annular chamber 20, and from thence downwardly through the reduced annular passage 23, with intermediate retardation and increased pressure, due to the increased lower diameter of closing portion 35 24 of the jet member *a*.

Thereafter the entire mixture enters the inner end portions of the several slots 25, first expanding therein due to the increased cross-section of the several ports at about 40 their middle, with final emission through the slightly tapering terminal portions for combustion outwardly through and beyond the end cavity 13.

The purpose of such cavity is to somewhat 45 reduce the velocity of the gaseous mixture flowing through the several channels 25 with a slight retardation, while giving the flame sufficient protection, greater stability, and an opportunity for mixture and combination in 50 the form of a single emission jet. There is therefore no tendency for the flame to blow away from the end of the tip when a given quantity of gases are passing through the pre-heating holes, in which, due to retardation of the current they receive a definite degree of pre-heating action from shell terminal 12.

By reason of the accurate adjustment of the proportions and amount of the mixture 55 being delivered through the pre-heating jets due to the adjusting shell, the torch is rendered somewhat independent of variations in individual valve control through the several main conduits.

65 It is well understood that it is necessary to

burn a comparatively large volume of combustible gas mixture in a small area in order to raise the temperature of the metal locally to combustion point in the shortest possible time. By my invention, due to the accurate control above described, I am able to very thoroughly mix the gas and oxygen, and secure the maximum flame temperature obtainable.

The metal having been thus preliminarily heated to the combustion point according to adopted best practice, the high pressure oxygen valve is then opened, admitting flow through conduit 2 to chamber 9, and then directly through the central opening 8 to the usual reduced outlet terminal port 37, for cutting in the usual way.

By reason of the outer tapering formation of slots 25 from their middle maximum cross-section, these slots in effect provide a plurality of holding reservoirs for the combustible mixture in the hottest portion of the tip, tending toward a more intimate mixture of the fuel components just prior to combustion.

The restricted areas and openings of the gas passages above described permit of using higher pressures of fuel gas, while the construction as a whole effects a very complete and thorough intimate mixture for the best results and even combustion.

It will be understood, of course, that the number and arrangement of the several ports and passages, or of the detail construction of the burner as a whole, may be changed or varied within the judgment of the designer or skilled mechanic, and with regard to the kind of work to be performed and the gaseous mixture employed. I therefore do not desire to be limited to the particular construction shown, but to include such variations as within the scope of the following claims.

What I claim is:

1. The combination with a head having a central oxygen supply and lateral oxygen and gas supplies respectively, of a centrally open oxygen jet member, a ported casing communicating with the gas supply, and a ported sleeve communicating with the lateral oxygen supply adjustably mounted in the casing having a terminal extension adapted to control said gas supply.

2. The combination with a head having a central oxygen supply and lateral oxygen and gas supplies respectively, of a centrally open oxygen jet member, a ported casing having an outer annular groove communicating with the gas supply, and a sleeve having threaded engagement with the casing provided with a transverse port communicating with the lateral oxygen supply and a tubular extension in opening and reducing relation to the gas communicating ports of the casing.

3. The combination with a head having a

- central oxygen supply and lateral oxygen and gas supplies respectively, of a centrally open oxygen jet member, a ported casing having an outer annular groove communicating with the gas supply, and a sleeve having threaded engagement with the casing provided with a transverse port communicating with the lateral oxygen supply and a tubular extension in opening and reducing relation to the gas communicating ports of the casing, and having supplemental transverse circulating ports. 5
4. In combination with a head having a central high pressure oxygen supply, a lateral pre-heating oxygen supply, and a lateral gas supply, of an outer casing mounted in the head having ports communicating with the gas supply, a centrally open jet member within the casing communicating with the high pressure oxygen supply, and a perforated sleeve between the casing and jet member having an adjusting plug engaging the end of the jet member. 10
5. In combination with a head having a central high pressure oxygen supply, a lateral pre-heating oxygen supply, and a lateral gas supply, of an outer casing mounted in the head having ports communicating with the gas supply, a centrally open jet member within the casing communicating with the high pressure oxygen supply, a transversely ported sleeve between the casing and jet member in threaded engagement with both and provided with a centrally open abutment engaging the end of the jet member. 15
6. In combination with a head having a central high pressure oxygen supply, a lateral pre-heating oxygen supply, and a lateral gas supply, of an outer casing mounted in the head having ports communicating with the gas supply, a centrally open jet member within the casing communicating with the high pressure oxygen supply, and a controlling sleeve for the gas supply having threaded engagement with the casing, head and jet member, having an inner abutment engaging the jet member and provided with a transverse port communicating with the lateral gas supply. 20
7. In combination with a head having a central high pressure oxygen supply, a lateral pre-heating oxygen supply, and a lateral gas supply, of an outer casing mounted in the head having ports communicating with the gas supply, a centrally open jet member within the casing communicating with the high pressure oxygen supply, and a controlling sleeve for the gas supply having threaded engagement with the casing, head and jet member, having an inner abutment in threaded engagement with the end of the sleeve bearing against the end of the jet member and provided with a transverse port communicating with the lateral gas supply. 25
8. In combination with a centrally open burner tip and a casing therefor having gas inlet ports, an intervening ported sleeve in threaded engagement with the burner tip and casing respectively provided with a limiting abutment in threaded engagement with the sleeve for the rear end of the burner tip. 70
9. In combination with a centrally open burner tip and a casing therefor having gas inlet ports, an intervening ported sleeve in threaded engagement with the burner tip and casing respectively having a portion located adjacent the gas inlet ports of the casing and provided with an adjustable limiting abutment in threaded engagement with the sleeve for the rear end of the burner tip. 75
10. In combination with a centrally open burner tip and a casing therefor having gas inlet ports, an intervening ported sleeve in threaded engagement with the burner tip and casing respectively having an annular terminal adapted to project across the gas inlet ports of the casing and provided with a perforated plug threaded in its opposite end adapted to engage the rear end of the burner tip. 80
11. In combination with the centrally open burner tip of a cutting torch and a surrounding casing therefor annularly spaced from the tip and provided with a series of annular gas inlet ports, an internally and externally threaded sleeve engaging the end of the tip and casing respectively and provided with oxygen inlet ports and a terminal extension operable across the gas inlet ports of the casing, and a perforated limiting plug for the rear end of the burner tip threaded in the opposite end of the sleeve. 85
12. In combination with the centrally open burner tip of a cutting torch and a surrounding casing therefor annularly spaced from the tip and provided with a series of annular gas inlet ports, an internally and externally threaded sleeve engaging the end of the tip and casing respectively and provided with oxygen inlet ports and a terminal extension operable across the gas inlet ports of the casing and transverse circulation ports backwardly from the end thereof, and a perforated limiting plug for the rear end of the burner tip threaded in the opposite end of the sleeve. 90
13. An adjustable controlling device for the gas supply to the burner tip of a cutting torch consisting of a tubular sleeve threaded externally and internally and provided with transverse circulation ports, a tubular ported shell extension at one end, and a centrally open plug threaded within the opposite end. 95
14. A cylindrical burner tip for cutting torches having a central oxygen passage and a tapered end and provided with longitudinal milled grooves extending backwardly from the end of the tapered portion, said grooves having their greatest depth between their ends. 100
15. A cylindrical burner tip for cutting 105
16. A cylindrical burner tip for cutting 110
17. A cylindrical burner tip for cutting 115
18. A cylindrical burner tip for cutting 120
19. A cylindrical burner tip for cutting 125
20. A cylindrical burner tip for cutting 130

torches having a central oxygen passage and a tapered end and provided with longitudinal milled grooves extending backwardly from the end of the tapered portion into the cylindrical portion and having their greatest 5 depth between their ends.

In testimony whereof I hereunto affix my signature:
